United States Patent Office

Des. 197,540
Patented Feb. 18, 1964

197,540

PHOTOGRAPHIC COPYING MACHINE

Frederick G. Knowles, Rochester, N.Y., assignor to Eastman Kodak Company, Rochester, N.Y., a corporation of New Jersey

Filed Aug. 9, 1963, Ser. No. 76,166

Term of patent 14 years

(Cl. D61—1)

FIG. 2

FIG. 1 is a front perspective view of a photographic copying machine showing my new design; and FIG. 2 is a rear perspective view thereof.

I claim:

The ornamental design for a photographic copying machine, as shown.
